DESIGN FOR A TRICYCLE

Arno Hecht, Babylon, N. Y., assignor to Henry Schirokauer, New York, N. Y.

Application October 25, 1945, Serial No. 123,160

Term of patent 14 years

(Cl. D34—15)

To all whom it may concern:

Be it known that I, Arno Hecht, a citizen of Germany, residing at Babylon, Long Island, State of New York, have invented a new, original, and ornamental Design for a Tricycle, of which the following is a specification, reference being had to the accompanying drawing, forming part thereof.

In the accompanying drawing:

Fig. 1 is a perspective view of a tricycle showing my new design;

Fig. 2 is a top plan view of the same; and
Fig. 3 is a side elevation of the same.

Figs. 2 and 3 are shown on a smaller scale than Fig. 1.

The essential features of my design reside in the portions shown in full lines on the drawing.

I claim:

The ornamental design for a tricycle, substantially as shown and described.

ARNO HECHT.
